P. K. DEDERICK.

Baling-Press.

No. 224,279.

Patented Feb. 10, 1880.

UNITED STATES PATENT OFFICE.

PETER K. DEDERICK, OF ALBANY, NEW YORK.

BALING-PRESS.

SPECIFICATION forming part of Letters Patent No. 224,279, dated February 10, 1880.

Application filed August 21, 1879.

To all whom it may concern:

Be it known that I, PETER K. DEDERICK, of Albany, Albany county, New York, have invented certain new and useful Improvements 5 in Baling-Presses; and I do hereby declare the following to be a full, clear, and exact description of the same, reference being had to the accompanying drawings, forming part of this specification, in which—

10 Figure 1 is a longitudinal vertical section; Fig. 2, a top plan, and Fig. 3 a modification of the gate and pitman.

Similar letters of reference in the several figures denote the same parts.

15 My improvements relate to that class of presses patented to me October 29, 1872, No. 132,566 and No. 132,639, and the various improvements and modifications of the same for which I have been granted patents since that 20 date, and relate more particularly to such of those presses as combine the horse-power and press in one machine, and in which the horse passes under the operating connections between the power and traverser.

25 It should be observed that in this machine I apply the power of the crank or toggle in a line directly, or nearly so, with the center of the traverser or resistance, and use an arched slide or gate to span the passage for the horse. 30 The frame of the press is also arched or framed so as to allow the horse to pass under the operating connections instead of over them, as in the presses referred to above.

A is the press-box; B, the bale-chamber; C, 35 the hopper; D D, the timbers which connect the press with the power, and between which the hopper or feed-orifice is located. E is the power-frame; F is a rod, chain, or other equivalent connection extending from the press to 40 the power underneath the horse-passage. G is a slide-bar to hold the rod or chain down during the pressing operation, and also to hold it up when the machine is being transported to and from the field. H is the gate; I, the crank; 45 K, the pitman or connection; L, the traverser; M, the sweep or horse-lever; N, the lug-plates, by means of which the power, through the lever, is applied.

The entire frame of the machine is constructed of strong timbers, and may be supported by truss-rods, if desired, and is mounted

on a truck, as shown. The lever M rotates over and around one pair of wheels, and the connection-timbers D D are at sufficient distance from the ground to admit of the horse 55 passing underneath them.

The crank I and pitman K work in the power-frame, as shown, and the slide or gate H is provided with ways, also in the power-frame, by which it is guided in its movements. 60 The other end of the gate H is firmly secured to the traverser L, and the gate itself forms an arch of equal height with the connection-timbers D D, and works between them. The crank or power shaft I passes through the 65 power-frame, and is extended or provided with an extension, which passes through the sweep and the lug-plate and into the bolster, and may also pass entirely through both bolster and axle, so as to form a king-bolt. Thus the connection between the press and truck passes through the sweep or horse-lever, and acts as the journal for the same. One end of the rod F is also secured to or near this extension, and the other to the press body. When the machine is used 70 without trucks the extension may rest in a step or box, or the shaft may turn on a pivot or rest under the shaft. The advantage of this arrangement of supporting the press at one end through or by means of the power- 75 shaft is that it may be operated by the horse-lever rotated around underneath the press, the circle or path traveled by the horses being entirely free from the bridges or other obstructions ordinarily employed to cover the operating connections. The rod F and the connection-timbers constitute a direct connection between the press and power in the form of a stirrup, the power end being the base or rest of the power, and the press end the resistance. 80

I have found it possible, by the free use of truss-rods, to so strengthen and stiffen the connection-timbers D D as to dispense with the rods F; but such construction requires more weight and expense in the machine, and 85 is not as satisfactory in operation. All other parts of this press are constructed in a manner similar to all of this class of presses, as shown and described in my preceding patents; hence 90 it is unnecessary to describe them particularly herein.

In order to accumulate power in compact

baling, I also propose to apply my eccentric or oval gear-power, as shown in my Patent No. 132,639, October 29, 1872, above referred to. In this case the power-shaft might be hollow, 5 and the connection between the press and truck pass through it or be pivoted in it. The gate H and pitman K might also be connected rigidly, as shown in Fig. 3, and thus form together an arched pitman. In this case the 10 one end could be pivoted through the traverser vertically, as shown, or connected with another pitman. This device would also require a brace, in order to properly strengthen the pitman, as the entire pitman must vibrate if 15 properly connected, and there could be no supporting-slides.

In operation, the horse is attached to the horse-lever and made to pass entirely around the two wheels of the truck in a full circle 20 and under the arched frame of the press and arched gate of the pitman. The hay is pitched in and pressed in sections, each round of the horse pressing a section, and the operation is continued as described in all the preceding 25 patents of this class hereinabove referred to.

In moving the press the sweep or horse-lever may be connected by a chain to the bale-chamber or press end, thus forming a reach, or it might be used for a pole to the 30 truck, if desired.

In the Letters Patent granted me February 1, 1870, antedated August 1, 1869, No. 99,295, is shown a mounted press in which the horse passes between the press and capstan and 35 around two of the wheels of the truck; but in this case the horse-power and press are two distinct machines, and the press shown is provided with a progressive power independent 40 of the capstan or horse-power, which is simply an auxiliary power, and not a part of press-power proper, and the horse passes over the connection between them.

In the press shown in Letters Patent granted me March 18, 1879, No. 213,280, the horse rotates a lever over and around a pair of truck-wheels, and passes under timbers which connect the power to the press; but in this construction, as in the one shown in the 1870 patent, the press and power are two machines connected, 50 and the press is provided with a complete power of its own, so as to be operated equally well by a belt from any motors; hence in both constructions the press proper is all at one side of the horse-circuit, and the horse simply makes a circuit of an auxiliary power mounted on the forward truck, and merely

passes under the timber connecting the two machines, but under no part of either machine proper.

In the present application the power-frame 60 and press constitute one machine, the base or support of the power being on the truck over which the horse-lever rotates, and the power exerted in the press-chamber on the other truck, and the two connected so as to form 65 an unyielding frame and one machine, and so as to admit of the horse passing under between the trucks to complete a circuit.

The axle under the power end of the press may be used either as the forward or rear 70 axle of the truck; but I prefer to make it the forward axle.

Having thus fully described my invention, I claim and desire to secure by Letters Patent—

1. The combination and connection of the truck and frame of the press by means of the power-shaft, as set forth.
2. The combination of the sweep or horse-lever with the power-shaft that passes through 80 said sweep and connects the truck and the frame of the press, substantially as described.
3. In a horizontal baling-press, the power end of the same, elevated and supported through or by means of the power-shaft, where 85 by the sweep or horse-lever is rotated underneath the frame of the press, as set forth.
4. In a horizontal baling-press, the combination of the horse-lever, rotated as set forth, with the arched frame or connection between 90 the base or foot of the power and the resistance or bale-chamber, substantially as and for the purpose set forth.

5. In a baling-press in which the horse-lever or sweep is rotated underneath the frame, 95 as set forth, the rod or equivalent connection F, connecting the press-chamber and the power end of the press, for the purpose set forth.

6. In a baling-press, the frame or gate H and pitman K, or arched pitman, in combination with the reciprocating traverser, substantially as and for the purpose set forth.

7. In a horizontal baling-press in which the hay is pressed in sections by a reciprocating traverser, the combination of the press-box A 105 and connection-timbers D, with the hopper or feed orifice through or between them, substantially as and for the purpose set forth.

P. K. DEDERICK.
